UNITED STATES PATENT OFFICE.

JOHN M. HOTHERSALL, OF BROOKLYN, NEW YORK, ASSIGNOR TO AMERICAN CAN COMPANY, OF NEW YORK, N. Y., A CORPORATION OF NEW JERSEY.

SELF-OPENING CAN.

1,244,610.

Specification of Letters Patent.

Patented Oct. 30, 1917.

Application filed August 16, 1915. Serial No. 45,650.

To all whom it may concern:

Be it known that I, JOHN M. HOTHERSALL, a citizen of the United States, residing in Brooklyn, in the county of Kings and State 5 of New York, have invented a new and useful Improvement in Self-Opening Cans, of which the following is a specification.

This invention relates in general to self-opening cans of the type frequently employed in the packaging of tobacco and the like and in which a soft closure is sealed to the open end of the body, a cover having a cutter being provided, said cutter serving to cut the soft closure about the center 15 of the can when the cover is rotated in proper position.

A principal object of this invention is the provision of a cutter of new and improved form and arranged in improved manner 20 on the cover.

Prior to my invention it has been generally the custom to provide a pair of slots in the cover in which is secured a cutter having a cutting tooth extending down 25 from one end. This arrangement has resulted in requiring considerable force in the operation of the cutter and in the formation of a more or less irregular and jagged cut. This invention aims to facilitate the 30 operation of the cutter and to produce a clean and smooth cut in severing the soft closure sheet already mentioned.

Another object of the invention is the accomplishment of these results without increasing the cost of manufacture of the finished package.

Other objects and advantages of the invention will be apparent as it is better understood from the following description 40 when considered in connection with the accompanying drawing illustrating a preferred embodiment thereof.

Referring to the drawings,

Figure 1 is a top plan view of a self-opening can embodying my invention;

Fig. 2 is a section taken substantially on the line 2—2 of Fig. 1; and

Fig. 3 is a large perspective view of the cutter.

In order to illustrate my invention I have 50 shown on the drawing a can body 4 closed at its top with the usual soft sheet metal closure 5. A slip cover 6 is provided and this cover is slotted at 7 for the reception of a cutter. The slots 7 are widely spaced 55 and of length approximating the width of the cutter. These slots extend in parallelism and hold the cutter in its cutting movement.

The cutter generally designated at 8 consists of an elongated strip curved to the arc of movement of the cutter and having its ends 9 disposed through the slots 7. The cutter is provided at substantially the center of its outer edge with a downwardly extending triangular tooth 10 sharpened on both its inclined edges 11 for cutting. The arrangement of the slots provides for a more direct pull in cutting and consequently permits a more easy operation. The cutter 70 may be readily formed from a sheet of metal by cutting it to proper shape and bending it so that the tooth 10 extends downwardly and so that the ends 9 may be inserted to the slot 7 and thereafter bent down to hold the 75 cutter in place.

It is thought that the invention and many of its attendant advantages will be understood from the foregoing description, and it will be apparent that various changes may 80 be made in the form, construction and arrangement of the parts without departing from the spirit and scope of the invention or sacrificing any of its material advantages, the form hereinbefore described being 85 merely a preferred embodiment thereof.

I claim:

1. A cover for a self-opening can and a cutter carried thereby, said cutter comprising a strip engaged at its ends in said cover 90 and having a cutting tooth extending downwardly from an edge of said strip.

2. A cover for a self-opening can comprising an elongated strip secured at its ends to said cover and having a cutting 95 tooth extending downwardly from the center of a side edge of said strip.

3. A cover for a self-opening can pro-

vided with a pair of widely spaced relatively short slots and a cutting element secured at its ends in said slots and having a cutting tooth extending downwardly from substantially its longitudinal center.

4. A cover for self-opening cans provided with widely spaced slots and a cutter secured at its ends in said slots, said cutter comprising an arcuately shaped strip with

a cutting tooth projecting downwardly 10 therefrom.

Signed in the presence of two subscribing witnesses.

JOHN M. HOTHERSALL.

Signed:

W. D. FOSTER,
ADOLPH E. J. HOERL.
